United States Patent Office.

PHILIP HINKLE, OF SAN FRANCISCO, CALIFORNIA.

Letters Patent No. 96,113, dated October 26, 1869.

IMPROVED IMPLEMENT FOR LAYING WOOD PAVEMENT.

The Schedule referred to in these Letters Patent and making part of the same.

To all whom it may concern:

Be it known that I, PHILIP HINKLE, of San Francisco, in the county of San Francisco, and State of California, have invented an Improved Implement for Laying Wood Pavement; and I do hereby declare that the following is a full and exact description of the same, reference being had to the accompanying drawings, and to the letters of reference marked thereon.

The nature of my invention is to provide an improved implement to be employed in the construction of wood or block pavements, so that the space between each block or row of blocks will be uniform in width, and on a straight line from curb to curb, and the interstices be packed with sand or rubble, for binding and holding the blocks to the foundation or bed upon which they rest.

Referring to the drawings—

Figure 1 is a plan or top view of the pavement and implement.

Figure 2 is a transverse view of pavement, showing a back view of the implement resting on the two end-blocks, with tamping-bar broken off.

Figure 3 is a longitudinal section of the pavement and implement, with tamping-bar.

A represents a thin strip of metal, or wood, set on edge, and to the front portion of which is attached a piece of metal, B, bent at right angles outwardly, and when in position, rests on the preceding row of blocks.

To the back part of the vertical gauge-board, at each end, are attached lugs, C C, bent at the same angle, and opposite the piece B.

A sufficient space, D, is formed between these guides, by vertical posts E E E, to which they are riveted. The space D is sufficient to admit the tamping-bar, by which the filling can be rammed before the gauge is removed.

In the bottom of the space is placed sand, which is tamped with the tamping-bar F, and when a sufficient height from the foundation is attained, the remaining space is filled with rubble, or other material.

In this connection, however, it will be well to state that after the first gauge is employed, and the first row of pavement laid, the second gauge should be pressed against the pavement, heretofore referred to, to keep the blocks in position, before the tamping of the first be performed; consequently two gauges must be employed, and be moved forward alternately.

By this means a true gauge is had, and every block may be set true, lengthwise and transversely, from curb to curb of the street, without keys or wedges.

Having thus described my invention, What I claim, and desire to secure by Letters Patent, is—

The gauge described, consisting of the vertical strip A, bent plate B, lugs C C, and posts E E, when arranged and adapted to the tamping-bar, as described, for the purpose set forth.

In witness whereof, I have hereunto set my hand and seal.

PHILIP HINKLE. [L. S.]
